FLOATING HOIST

John N. Locki, St. Louis, Mo.

Application June 19, 1947, Serial No. 755,554

14 Claims. (Cl. 212—3)

1

This invention relates to floating hoists, and more particularly to floating hoists for diving apparatus.

Among the several objects of the invention may be noted the provision of a hoist for diving apparatus, for use on salvage vessels or the like, adapted to permit diving operations in rough and turbulent waters; the provision of a hoist of the class described which compensates for wave-induced motion of the vessel to permit diving operations under adverse weather conditions; the provision of a hoist of this class adapted both for shallow diving operations by a diver in a flexible diving suit and for deeper diving operations by a diver in a rigid-walled diving chamber or compartment; and the provision of a hoist such as described adapted to traverse a diving chamber or compartment, even in rough seas, so that a diver therein may carry on sub-sea exploration or other operation over a considerable area from an anchored salvage vessel. Other objects will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which one of various possible embodiments of the invention is illustrated,

Fig. 1 is a plan view of a hoist of the invention, certain parts being broken away;

Fig. 2 is a side elevation thereof, viewed along a fore-and-aft direction on a vessel upon which the hoist is mounted;

Fig. 3 is an enlarged vertical longitudinal section taken on line 3—3 of Fig. 1;

Fig. 4 is a vertical transverse section taken on line 4—4 of Fig. 2;

Figs. 5 and 6 are diagrammatic side elevations of the hoist on a reduced scale, viewed in fore-and-aft direction with respect to the vessel, and illustrating different positions of certain elements of the hoist for different positions of the vessel; and,

Fig. 7 is a fragmentary diagrammatic plan view illustrating various positions of a jib of the hoist of this invention.

Similar reference characters indicate corresponding parts throughout the several views of the drawings.

Heretofore it has been difficult to carry on diving operations from a salvage vessel or the

2

like in rough seas. The motion of the vessel under such adverse weather conditions has made it so difficult to control the diving lines that diving operations have generally had to be abandoned for the safety of the diver and the diving equipment until the sea subsides. It has also been practically impossible for the diver to carry on any work or observations if the diving lines are being raised and lowered in accordance with the rising and falling motion of the vessel, apart from considerations of safety. With the hoist of this invention, however, compensation is made for the rising and falling motion of the vessel so that such motion has little or no effect upon the diving lines. This makes it possible for the diver to work in safety even in rough seas.

Referring now to the drawings, the hoist of this invention is shown to comprise a mast 1 supported upon the deck of a floating support, such as a salvage or like vessel 3, as by being mounted on a platform 5 on the deck of the vessel. The mast is illustrated as comprising a pair of uprights 7 arranged so that they are spaced longitudinally of the vessel. The mast is braced transversely of the vessel by struts 9. A shaft 11 is mounted in the upper ends of uprights 7 extending longitudinally of the vessel. This shaft provides a pivotal mounting for a boom 13 which extends athwartship and is adapted to swing in a generally vertical plane.

The boom 13 is of such length as to extend beyond the side of the vessel throughout a considerable arc of its pivotal movement about the axis of shaft 11. It comprises a pair of side members 15 connected and braced by latticework 17. Side members 15 extend past the pivot to provide supports for an adjustable counterweight 19. The latter is supported between the extensions of side members 15 for longitudinal movement with respect to the boom by means of ears 20, which project laterally from the counterweight and slide on the upper surfaces of the side members.

The counterweight is adapted to be adjusted toward and away from the pivotal axis of the boom to balance the weight of the boom and elements carried by the boom. As illustrated, an adjusting screw 21 is threaded through the counterweight longitudinally with respect to the boom. Screw 21 is journalled for rotation and fixed against axial movement in bearing members 23 mounted on the extensions of side members 15. The screw may by any suitable means be turned to slide the counterweight longitudinally with respect to the boom. As illustrated, a pulley 25

is fixed on the inboard end of screw 21 and an endless cable 27 is trained around the pulley for turning the screw in either direction.

Shaft 11 carries a pair of guide pulleys 29 aligned with a pair of outboard guide pulleys 31 on a shaft 33 mounted in the outboard ends of the side members 15 of the boom 13. Anchor cables 35 carrying an anchor 37 are trained over these pulleys and are wound around the hoisting drum of an anchor winch 39 mounted on platform 5. The arrangement is such that the anchor cables may be payed out from the winch to lower the anchor and taken in to raise the anchor.

Shaft 11 also carries a guide pulley 41 aligned with an outboard guide pulley 43 (Fig. 4) mounted on shaft 33. A hoist line 45 carrying an elevator 47 is trained over these pulleys and is wound around the hoisting drum of an elevator winch 49 mounted on platform 5. The elevator 47 comprises a diver's platform 51 carried by cage bars 53. The latter are connected at their upper ends to an eye 55 by which the elevator is suspended from a hook 57 on the end of hoist line 45. The anchor cables 35 extend through guide eyes 59 provided on platform 51 for guiding the elevator 47 in its vertical movement. The arrangement is such that the elevator 47 may be raised and lowered by paying out or taking up the hoist line 45.

The elevator 47 is particularly for the purpose of raising and lowering a diver wearing a flexible diving suit for diving operations at shallow depths. Additional pulleys 61 and 63 are provided on shafts 11 and 33, respectively, for the necessary diving lines coupled to the diver's suit, such as an air line and a communication line. A diver's attendant's platform 65 may be suspended at the outboard end of the boom, as illustrated at 67, so that the attendant has access to the diving lines before they pass over the pulleys 63. Thus, the attendant may receive hand signals from the diver made by jerking on the diving lines in the event that no other mode of communication is possible.

For carrying out diving operations at a greater depth than possible by divers in flexible diving suits, provision is made for raising and lowering a rigid-walled diving chamber, such as the observation chamber 71 illustrated, and for traversing this chamber to permit operations over a considerable area from the anchored vessel 3. To this end, the hoist includes an auxiliary boom or jib 73 mounted on the boom 13 for swinging movement therewith in a vertical plane, and also mounted to swing laterally with respect to the boom and for longitudinal movement in the direction of the length of the jib.

As illustrated, the mounting for jib 73 comprises a bearing platform 75 supported by means of pedestals 77 on the side members 15 of boom 13 in position spanning the side members above shaft 11. A jib guide housing 79 rests slidably on the platform 75 and is pivoted for swinging movement thereon about an axis perpendicular to the plane of the boom by means of a tubular pivot pin 81. The jib 73, which comprises an elongate spar of greater length than the boom, extends slidably through the guide housing 79. Thus, it may pivot laterally with housing 79 and be moved in the direction of its length with respect to the housing. The bearing platform 75 has an edge 80, formed on an arc about the axis of pivot pin 81. A depending guide clip 83 on

housing 79 embraces this edge to guide the housing in its pivotal movement.

The jib 73 extends beyond the outboard end of the boom and has an outboard guide pulley 85 for a diving chamber hoist line 87 mounted upon its outboard end. Line 87 extends from pulley 85 over a guide pulley 89 mounted on the jib guide housing 79 adjacent pivot pin 81, thence through a longitudinal slot 91 in the jib and through the tubular pivot pin to a winch 93 on platform 5. The diving chamber is suspended from the end of line 87 and may be raised and lowered by taking up or paying out the line.

The jib 73 may be moved or traversed longitudinally by any suitable reciprocating drive means for the purpose. As illustrated, it is adapted to be reciprocated by means of a cable 95 having its ends fixed to the jib at 97 and 99 and intermediately wound around a drum 101. The latter is mounted on a shaft 103 journaled in the jib guide housing 79. Shaft 103 may be driven in any suitable way to take up cable 95 on one side of drum 101 and pay it out on the other, thus moving the jib longitudinally with respect to the housing 79. As illustrated, shaft 103 is driven by a reversible motor and speed-reduction drive unit generally designated 105. The jib may be swung laterally on pivot pin 81 by means of cables (not shown) connected to its outboard end and manipulated from the deck of the vessel. A yoke 107 is mounted upon the boom 13 adjacent its outboard end to support the jib 73 while permitting longitudinal and lateral movements thereof relative to the boom.

The bearing platform 75 is preferably removably mounted on the boom 13 so that it may be removed if deep-sea diving operations utilizing the diving chamber 71 are not contemplated. To this end, pedestals 77 may be removably fastened to the side members 15 of the boom by readily removable fasteners such as bolts. Upon removal of such fasteners, the jib 73, platform 75 and housing 79 may be removed as a unit from the boom.

Figs. 5 and 6 diagrammatically illustrate the mode of operation of the hoist for diving operations at relatively shallow depths. The jib 73 and associated elements are not shown in these figures inasmuch as they are not used for such operations. When the hoist is not in use, the anchor 37 and the elevator 47 are usually raised and swung aboard the vessel by raising the boom 13 to the extreme dotted line position illustrated in Fig. 5. The boom may be maintained in such position by a guy wire 109 having its lower end releasably anchored to any suitable means on the hoist or elsewhere on the deck of the vessel. After the vessel 3 has been anchored at the site of operations, the guy wire 109 is released and the boom is lowered to extend generally horizontally beyond the site of the vessel. Anchor cables 35 are then payed out until anchor 37 rests upon the bed of the body of water. The counterweight 19 is adjusted to such position that it balances or overbalances the weight of the boom, the elevator 47, the diver on the elevator, the platform 65, elevator hoist line 45 and any other elements carried by the boom, but does not overbalance the weight of anchor 37. Thus the boom is biased by the counterweight to pivot upward (clockwise as viewed in Figs. 5 and 6), its movement being limited by engagement of the outboard anchor cable pulleys 31 with the anchor cables 35. The anchor cables are preferably payed out to such an extent that, with the anchor

37 resting on the bed of the body of water, the boom is approximately horizontal when the vessel is at a normal elevation above the bed, as illustrated in Fig. 5. The diver is lowered in elevator 47 to the bottom by paying out the line

45. The elevator is guided as it descends by the anchor cables 35 extending through the elevator guides 59 (see the position of the elevator in Fig. 5). The lowermost position of the elevator is at the anchor as shown in Fig. 6.

The hoist functions to compensate for rising and falling motions of the vessel occasioned by a rough sea so that the outboard end of the boom 13 may remain at a substantially constant elevation above the water bed despite such motions of the vessel. If the vessel should rise from its normal elevation of Fig. 5 to the elevation illustrated in Fig. 6, the boom pivots downward, being restrained by anchor cables 35. The length of the latter from the winch 39 to the anchor 37 remains constant. Fig. 6 also illustrates the vessel as having rolled to some extent from its even keel position of Fig. 5 and shows how the boom also compensates for rolling of the vessel. If the vessel should fall from its normal elevation of Fig. 5, the boom will pivot upward under the bias of counterweight 19 to maintain the anchor cables 35 taut and to maintain the outboard end of the boom at the stated substantially constant elevation.

Since the outboard end of the boom thus remains at a substantially constant elevation above the bed of the body of water, rising and falling motions of the vessel have no substantial effect upon the elevator 47 and it remains upon the bed (or at any other elevation to which it has been lowered). Also, rising and falling motions of the vessel have no substantial effect upon the length of the diver's lines and it is not necessary to pay out a considerable length of such lines, as is usually necessary to provide enough slack to permit the diver to move about without being unduly restrained by the lines and to avoid danger of the lines becoming snagged or snapped. Further, the compensation for the rising and falling motions of the vessel permits the elevator (and the diver) to be lowered to and raised from the desired working depth at a uniform rate. That is, the elevator 47 does not rise and fall in unison with rising and falling motions of the vessel and there is no danger of snapping the elevator cable and the diver's lines.

For diving operations at a greater depth than feasible for a diver in a flexible diving suit, the diving chamber 71 and jib 73 are utilized. The anchor 37 is lowered to rest upon the bed of the body of water as previously described. The counterweight 19 is adjusted to such position that it overbalances the weight of the boom 13 and the various elements carried by the boom, including the jib 73, the diving chamber 71 and the diver therein, but does not overbalance the weight of anchor 37. The diving chamber 71 is then lowered to the desired depth by paying out the line 87 from winch 93. Since the weight of the boom, jib and diving chamber is overbalanced by the counterweight 19, the boom and jib compensate for rising and falling motions of the vessel in the manner previously described.

Thus, the diving chamber 71 may be lowered and raised at a uniform rate, despite the motion of the vessel, to avoid snapping of the line 87 and other lines which may be connected to the chamber. The chamber will remain at any depth to which it has been lowered since rising and falling

motions of the vessel have no effect to raise and lower the chamber. This enables the diver in the chamber to make the necessary observations or perform other operations from a substantially stationary, steady position.

5 If it is desired to move the chamber 71 about for exploration, the jib 73 may be moved in or out by driving shaft 103 in the appropriate direction, and may be swung laterally about the axis of pivot pin 81 in the manner previously described, and as illustrated in Fig. 7. Thus, operations may be carried on over a considerable area, even though the vessel 3 is anchored and the diver is confined within chamber 71, and despite rough seas.

10 In view of the above, it will be seen that the several objects of the invention are achieved and other advantageous results attained.

15 As many changes could be made in the above constructions without departing from the scope of the invention, it is intended that all matter contained in the above description or shown in the accompanying drawings shall be interpreted as illustrative and not in a limiting sense.

20 25 I claim:

1. A floating hoist comprising a floating support, an elongate member pivoted on said support for swinging movement in a generally vertical plane and extending beyond the support, an anchor suspended by an anchor cable from said member, said cable running from said anchor over an outboard guide on said member to hoisting means on said support, a hoist line for raising and lowering a load suspended from said member, said line running from said load over an outboard guide on said member to hoisting means on said support, and means acting on said member applying torque tending to swing said member on its pivot for overbalancing its weight and the weight of said load but not the weight of said anchor to bias said member to swing upward about its pivot in opposition to the restraint of the anchor cable.

2. A floating hoist comprising a floating support, a mast stepped on the support, a boom pivoted on the mast for swinging movement in a generally vertical plane and extending from its pivot beyond the support, an anchor suspended by an anchor cable from the boom, said anchor cable running from said anchor over an outboard guide on said boom to hoisting means on said support, an elevator suspended from said boom by means of a hoist line running from the elevator over an outboard guide on said boom to hoisting means on said support, and adjustable means acting upon an extension of the boom on the side of its pivot opposite said guides applying torque tending to swing the boom on its pivot for overbalancing the weight of said boom, elevator and a load thereon but not the weight of said anchor, thereby to bias the boom to swing upward about its pivot in opposition to the restraint of the anchor cable.

3. A floating hoist as set forth in claim 2, 65 wherein said adjustable biasing means comprises a counterweight carried by the extension of said boom for movement toward and away from its pivot, and means for moving said counterweight toward and away from said pivot and retaining it in adjusted position with respect thereto.

4. A floating hoist as set forth in claim 2, wherein the elevator is provided with guide means cooperable with the anchor cable for guiding the elevator for substantially vertical movement.

70 5. A floating hoist comprising a floating sup-

port, a boom pivoted on said support for swinging movement in a generally vertical plane and extending from its pivot beyond said support, an anchor suspended by an anchor cable from the boom, said anchor cable running from said anchor over an outboard guide on said boom to hoisting means on said support, a jib carried by said boom for vertical swinging movement therewith and also for lateral swinging movement and longitudinal reciprocating movement with respect to the boom, a hoist line for raising and lowering a load suspended from said jib, said line running from said load over an outboard guide on said jib to hoisting means on said support, and means acting on the boom for overbalancing its weight and the weight of said jib and load but not the weight of said anchor, thereby to bias said boom and jib to swing upward about said pivot in opposition to the restraint of said anchor cable.

6. A floating hoist comprising a floating support, a boom pivoted on said support for swinging movement in a generally vertical plane and extending from its pivot beyond said support, an anchor suspended by an anchor cable from the boom, said anchor cable running from said anchor over an outboard guide on said boom to hoisting means on said support, a jib guide mounted on said boom for swinging movement about an axis perpendicular to the pivot axis of the boom, an elongate jib mounted for longitudinal sliding movement in said guide and for swinging movement therewith, a hoist line for raising and lowering a load suspended from said jib, said line running from said load over an outboard guide on said jib to hoisting means on said support, and means acting on the boom for overbalancing its weight and the weight of said jib and load but not the weight of said anchor, thereby to bias said boom and jib to swing upward about said pivot in opposition to the restraint of said anchor cable.

7. A floating hoist as set forth in claim 6, wherein said jib guide is pivoted on said boom by means of a tubular pivot pin, and said hoist line runs from said outboard guide on said jib through said pin and thence to the hoisting means for said line and load.

8. A floating hoist as set forth in claim 6, further including means mounted on said jib guide for longitudinally reciprocating the jib.

9. In a hoist of the class described, a mast, a projecting boom pivoted to the upper end of said mast for vertical swinging movement, said boom having an extension from said pivot, adjustable counterbalancing means acting on said extension adapted to be adjusted to overbalance the weight of said projecting boom and loads thereon, an anchor suspended by a cable running from said anchor over a guide on the projecting portion of said boom and over a guide at the pivot portion of the boom to hoisting means, and a load platform suspended by a hoist line running therefrom over a guide on the free projecting end of the boom and a guide near the pivot portion of the boom to hoisting means.

10. In a hoist of the class described, a mast, a boom pivoted near one end to the upper end of said mast for vertical swinging movement, said boom having an extension from said end beyond said pivot, adjustable counterbalancing means acting on said extension adapted to be adjusted to overbalance the weight of said boom and loads thereon, an anchor suspended by a pair of anchor cables running from said anchor over guides on the free end of said boom and over guides on the pivot end of the boom to hoisting means, a jib mounted on the boom for vertical swinging movement therewith and lateral swinging movement with respect thereto, and a hoist line for raising and lowering a load suspended from the jib running from said load over a guide on the jib to hoisting means.

over guides on the pivot end of the boom to hoisting means, a load platform suspended by a hoist line running therefrom over a guide on the free end of the boom and a guide on the pivot end of the boom to hoisting means, each of said pair of anchor cables running through guide means on the platform, whereby the anchor cables function as guides for substantially vertical movement of the platform.

11. In a hoist of the class described, a mast, a projecting boom pivoted to the upper end of said mast for vertical swinging movement, said boom having an extension from said pivot, adjustable counterbalancing means acting on said extension adapted to be adjusted to overbalance the weight of said projecting boom and loads thereon, an anchor suspended by a cable running from said anchor over a guide on the projecting portion of said boom and over a guide at the pivot portion of the boom to hoisting means, a load platform suspended by a hoist line running therefrom over a guide on the free projecting end of the boom and a guide near the pivot portion of the boom to hoisting means, a jib mounted on the boom for vertical swinging movement therewith and lateral swinging movement with respect thereto, and a hoist line for raising and lowering a load suspended from the jib running from said load over a guide on the jib to hoisting means.

12. In a hoist of the class described, a mast, a projecting boom pivoted to the upper end of said mast for vertical swinging movement, said boom having an extension from said pivot, adjustable counterbalancing means acting on said extension adapted to be adjusted to overbalance the weight of said projecting boom and loads thereon, an anchor suspended by a cable running from said anchor over a guide on the projecting portion of said boom and over a guide at the pivot portion of the boom to hoisting means, and a load platform suspended by a hoist line running therefrom over a guide on the free projecting end of the boom and a guide near the pivot portion of the boom to hoisting means, a jib mounted on the boom for vertical swinging movement therewith and for lateral swinging movement and longitudinal reciprocating movement with respect thereto, and a hoist line for raising and lowering a load suspended from the jib running from said load over a guide on the jib to hoisting means.

13. In a hoist of the class described, a mast, a boom pivoted near one end to the upper end of said mast for vertical swinging movement, said boom having an extension from said end beyond said pivot, adjustable counterbalancing means acting on said extension adapted to be adjusted to overbalance the weight of said boom and loads thereon, an anchor suspended by a pair of anchor cables running from said anchor over guides on the free end of said boom and over guides on the pivot end of the boom to hoisting means, a load platform suspended by a hoist line running therefrom over a guide on the free end of the boom and a guide on the pivot end of the boom to hoisting means, each of said pair of anchor cables running through guide means on the platform, whereby the anchor cables function as guides for substantially vertical movement of the platform, a jib mounted on the boom for vertical swinging movement therewith and lateral swinging movement with respect thereto, and a hoist line for raising and lowering a load suspended from the jib running from said load over a guide on the jib to hoisting means.

14. In a hoist of the class described, a mast, a boom pivoted near one end to the upper end of said mast for vertical swinging movement, said boom having an extension from said end beyond said pivot, adjustable counterbalancing means acting on said extension adapted to be adjusted to overbalance the weight of said boom and loads thereon, an anchor suspended by a pair of anchor cables running from said anchor over guides on the free end of said boom and over guides on the pivot end of the boom to hoisting means, a load platform suspended by a hoist line running therefrom over a guide on the free end of the boom and a guide on the pivot end of the boom to hoisting means, each of said pair of anchor cables running through guide means on the platform, whereby the anchor cables function as guides for substantially vertical movement of the platform, a jib mounted on the boom for vertical swinging movement therewith and for lateral 20 swinging movement and longitudinal reciprocating movement.

5

ing movement with respect thereto, and a hoist line for raising and lowering a load suspended from the jib running from said load over a guide on the jib to hoisting means.
